UNITED STATES PATENT OFFICE.

RAY W. HARROUN, OF INDIANAPOLIS, INDIANA, ASSIGNOR, BY MESNE ASSIGNMENTS,
TO INVINCIBLE MANUFACTURING COMPANY, A CORPORATION OF PENNSYLVANIA.

CARBURETER.

1,135,689.

Specification of Letters Patent. Patented Apr. 13, 1915.

Application filed August 8, 1912. Serial No. 714,065.

To all whom it may concern:

Be it known that I, RAY W. HARROUN, a citizen of the United States, residing at Indianapolis, in the county of Marion and State of Indiana, have invented certain new and useful Improvements in Carbureters, of which the following is a specification.

My invention relates to improvements in carbureters and has for its general object to provide a carbureter construction which shall be capable of novel automatic response to keep the richness of the mixture at all times satisfactory to the needs of the engine supplied.

Another object of my invention is to provide a casing structure so arranged that the carbureter shall be sufficiently warmed and condensation practically eliminated by an advantageous collocation of the mixing chamber, the fuel chamber, and the associated passageways, so that the carbureter shall be warmed, as on cold days, more quickly after beginning of operation of the device than would be the case if the device were water-jacketed.

Another object of my invention is to provide an advantageous nozzle-operating means such that the richness of the mixture, as upon quick opening of the throttle, will be automatically increased above that which prevails in the normal running of the device, so that the parts need not be adjusted to supply a richer mixture than necessary under normal running conditions in order that the mixture shall be rich enough upon the occasions requiring a charge of unusual richness, and to this end my invention contemplates provision of a novel valve for an auxiliary air inlet to the mixing chamber and novel connections between such valve and the valve for the carbureting nozzle.

Other objects of my invention, structural and functional, will become apparent from a consideration of the following description taken in conjunction with the drawings, wherein—

Figure 1 is a vertical central section through a carbureter constructed in accordance with my invention; Fig. 2 is a section on line 2—2 of Fig. 1; Fig. 3 is a section on line 3—3 of Fig. 1; and Fig. 4 is a section on line 4—4 of Fig. 1.

In the drawings, A indicates in general a casing member in the interior of which is provided a mixing chamber 5 open to the

outlet 6, the chamber being bounded in part by top wall 7 and partition wall 7' to provide within the casing A a passage 9 constituting an auxiliary air-supply passage for valve-controlled communication with chamber 5 through a port 8, and constant communication through passage 9' with the air inlet 10. I prefer that the walls of the casing A respectively above and below the wall 7 which divides the mixing chamber 5 from the auxiliary air-supply passage 9 be perforated for ready access to the valve to be described, and thus I have shown the upper wall to be perforated at 11 and provided with a suitable closure 12 secured in the perforation by means of a split spring 13, and the lower wall to be perforated and provided with screw threads as at 14 for engagement of a suitable guide and supporting member 15 for association with the valve and retard means to be hereafter described.

In the bottom of the casing A, preferably under the outlet 6, I provide a tubular extension 16, constituting the carbureting tube or chamber leading to the mixing chamber, 80 the interior of which is suitably restricted as at 17 for coaction with a suitable nozzle to be described. At the end of extension 16 is a cross member 16', preferably integral therewith, which is transversely bored as at 18 and vertically bored and screw threaded both above and below the transverse bore as at 19 and 20, to receive respectively the nozzle and drain cock to be described.

A second casing member B is adapted to 90 coact with the casing member A, around the tubular member 16, to provide a fluid containing chamber. For such coaction with the casing member A the upper edge of the casing member B is shaped for close contact 95 with the lower wall of casing member A as at 21, and is provided with an interior wall 22 extending inwardly from the side wall of the casing member B, slightly above the bottom wall thereof, for coaction with the lower edge of the tubular member 16, said parts being suitably shaped to receive a joint packing member 23 so that the space 24 above said horizontal wall, constituting the fuel chamber, is suitably separated from the space 105 25 thereunder which communicates through the carbureting tube 16 with the mixing chamber 5. Extending upwardly from the space 25 the casing B provides an air duct 26 communicating through perforations 27 in 110

the base of casing member A with the inlet 10, and constituting primary inlets leading through the carbureting tube.

To retain the casing member B in the position of coaction with casing A shown in Fig. 1, I preferably provide a pet cock 28 having a pipe 29 extending through a perforation 30 in the bottom wall of the casing member B, said pipe 29 being screw threaded at its end for engagement in the screw threaded bore 20 of the cross piece 16', the pet cock thus being in a suitable position to drain the liquid fuel from chamber 24 and at the same time providing a simple and convenient means for maintaining the parts in assembled position.

Engaging in the screw-threaded bore 19, I provide a suitable nozzle 31 having a valve seat 32, lateral perforations 33 thereabove, and a guide portion 34 to receive the needle valve 35 which is held toward closed position by spring 36 at one end secured in lug 37 on the interior of the wall 7', and at its other end engaging in a slot 38 in the end of the valve needle 35.

It will be understood that the general casing arrangement described provides for advantageous retention of heat from the air passing therethrough by correlation of the mixing chamber, the fuel chamber, and the various air inlets and the outlet, so that such various divisions of the device have walls in common. By connecting the inlet 10 through a pipe C with a jacket J surrounding the engine exhaust pipe P, the air introduced into the carburetor may be adequately heated, and since the exhaust pipe gets hot almost as soon as the engine starts running, the heated condition of the air is secured very promptly after the engine starts.

Within the fuel chamber 24, I provide the usual float 39 for operation of the valve 40 to control the height of fluid in the chamber 24, any suitable connections between the float 39 and valve 40 being provided as for instance a pivoted lever 41 to one arm of which the float is secured as at 42 and the other arm of which carries the stem 43 of the valve 40, the connections between the lever 41 and the stem 43 being of some suitable nature, as shown at 44, to accommodate the inclinations of the lever incident to operation of the float 39. As a further feature of the usual carburetor construction a throttle valve 45 is shown in the exhaust outlet for operation in usual fashion.

The valve construction for the auxiliary air inlet port 8 is such as to cause an initial movement of the fluid-controlling needle valve 35 before the auxiliary inlet port 8 is opened, so that upon sudden opening of the throttle, 45, the resultant increase in suction may open the gasoline valve to enrich the mixture before port 8 is opened. To this end I provide a valve 46 pro-

vided with openings between its arms 46' and secured as by pin 47' to stem 47 which has two diameters separated by shoulder 48 for purposes described hereafter, and upon said valve 46 I mount a diaphragm 49, of leather or other suitable material, secured near its edges, as at 50, to the underside of the valve so that the central portion of said diaphragm is movable before the valve is moved to open port 8, said diaphragm being of course perforated as at 51 for passage therethrough of the stem 47. The perforation 51 is preferably larger in diameter than the reduced portion of the stem 47 to accommodate a sleeve member 52 loose on the reduced portion of the stem 47 for free movement between the shoulder 48 and the frame 46. The sleeve 52 provides a flange 53, preferably midway thereof, and between said flange 53 and a flange 54 of sleeve 55, securely mounted upon sleeve 52, diaphragm 49 is engaged. It will thus be apparent that the vertically movable part composed of sleeves 52 and 53 is movable with the diaphragm, and that its downward movement relative to the valve proper is limited by shoulder 48 while in normal position it abuts against the valve. The sleeve 55 is provided upon its lower edge with a flange 56 between which and the bottom closure 15 a compression spring 57, surrounding the stem 47 and stem guide 58, engages to hold the diaphragm-carried sleeve in uppermost position and through it to hold the valve in closed position. The flange 56 is further extended as at 59 for coaction with a means for connection of the auxiliary air valve 46, with the gasoline valve 35.

The connection between the closure for the auxiliary inlet described and the needle valve 35 preferably takes the form of walking beam 60 provided at a suitable point between its ends with a deflected portion 61 for engagement upon the pivotal adjustable support 62 and at one end is provided with a flat disk 63 lying in a vertical plane for engagement in a slot 64 of the needle valve 35, so that in obvious fashion rocking of the beam 60 will cause the raising or lowering of valve 35, the engagement of disk 63 in slot 64 being such as to accommodate variation in the inclination of the beam 60. The other end of the beam 60 preferably provides two arms 65 each provided at its end with an enlargement 66 extending upwardly and having a curved upper edge for abutment against the extension 59 of flange 56, which it will be remembered is moved downwardly by operation of the diaphragm 49. Spring 36 tends to hold this end of the beam 60 in its upper-most position to receive such abutment.

The support 62 for the walking beam preferably takes the form of an eccentric whereby the pivot point of the beam may be

changed and the movement of needle valve 35, following given movement of the diaphragm-carried sleeve, varied. Thus, I provide an arm 67 extending transversely across 5 the casing and journaled in the walls thereof, said arm being deflected at 68 whereby the beam overlies it, so that in obvious fashion rotation of the arm 67, as by means of lever 69 connected by a link 70 to a suitable manually-movable part on the automobile, the position of the pivot point of the beam 60 may be varied with respect to the 10 valves.

The stem 47 extends through the closure 15 member 15 within the guide 58, and at its outer end carries a horizontal piston member 71 having a somewhat smaller diameter than that of a cylinder structure 72 carried by the closure member 15 and adapted to 20 contain a body of oil by means of which the movement of the piston member 71 and consequently the movement of the frame 46 through stem 47 and of the inlet-closing edges of the diaphragm 49 is uniformly retarded. 25 When the diaphragm is depressed by reduction of pressure in the mixing chamber, obviously the weight of the auxiliary valve together with pressure upon its upper side will cause the opening of the valve subject, 30 of course, to the retard means.

The operation of the device is as follows: The inlet 10, is preferably connected with the exhaust-pipe jacket or other engine-heated part, and thus the air entering the 35 carburetor is warmed. As soon as the pressure above the outlet 6 is reduced incident to the initial operation of the engine, throttle 45 being opened, air is drawn from inlet 10 through the perforations 27 and primary air 40 inlet 26 to the lower space 25 of the casing member B, and thence up within the carbureting tube 16, imparting some of its heat to all of these parts in its passage thereby to warm the gasoline and all of the walls on 45 which the gasoline vapor might condense. After passing through the restricted portion 17 of the carbureting tube the air receives fuel from the nozzle openings 33, the needle 50 having been properly raised by movement of beam 60. This beam, may, of course, be hand-adjusted by operation of lever 69, and furthermore the suddenly-imposed suction in mixing chamber 5 causes diaphragm 49 to be depressed thereby to 55 rock the beam 60 and further open the valve 35. During this initial operation auxiliary valve 46 closes the auxiliary air inlet port 8 as a result of the retard device operating through stem 47, but the valve part 46 tends 60 to follow the sleeve 52 downward on account of its weight and the pressure thereabove, as rapidly as the dash-pot resistance will permit. When starting it is preferable to operate the eccentric support 68 for the nozzle 65 operating beam 60 so that the initial open-

ing of the nozzle will result in a richer mixture than under normal operating conditions. When the engine is running properly, the eccentric 62 is returned to normal height, and under these conditions the heated air 7 from inlet 10 enters casing A, a portion of such heated air passing down through the primary inlet 26 and up through the carbureting tube, always lending some of its heat to the surrounding parts and being carbureted in its passage past the nozzle openings 33. When the suction is sufficient to cause opening of the auxiliary valve 46 the remaining portion of the air from inlet 10, (surrounding the outlet 6 and mixing chamber 5, and therefore lending some of its heat to said parts) passes through the auxiliary air supply passage 9 and port 8 into mixing chamber 5 to join the carbureted air from the tube 16. In this operation, it will be obvious that the valve, its retard means, the connection between the beam 60 and the valve, and the beam, operated by the diaphragm 49, provide an arrangement where all variations incident to the use of the carburetor, such as sudden increase in suction and the like, are automatically taken care of by my device, without need to compromise the normal running condition in order to take care of the less frequent occurrences of use, for it will be obvious that with the auxiliary air inlet 8 held closed (by retard) and the carbureting nozzle in tube 16 opened (by diaphragm) greater suction and consequently enhanced carburation will 95 result in said carbureting tube, and that the more sudden the variation in pressure the more marked will be this operation of the device, so that the device is both efficient and economical. Advantages other than 100 those which I have mentioned above will, of course, be apparent to those skilled in the art from the above description of the device and its operation, and need not here be elaborated.

While I have herein described a single embodiment of my invention, it will be apparent to those skilled in the art that my teachings may be variously embodied and that numerous changes may be made in the 105 device without departing from the spirit of the invention and within the scope of the appended claims.

What I claim is:

1. In a carburetor, a casing providing a mixing chamber and a fuel chamber, said casing being shaped to provide a primary air inlet passing around the fuel chamber in contact with the wall thereof to a space below said fuel chamber and a carbureting tube 120 communicating between said space below the fuel chamber and said mixing chamber.
2. In a carburetor, the combination of a casing providing a mixing chamber, said casing having a tubular member extending 125

therefrom constituting a carbureting tube leading to the mixing chamber, a second casing member providing with said first casing a fuel chamber surrounding said tubular extension, a nozzle, means at the end of said tubular member for supporting the nozzle therein having communication with the fuel chamber, means on said tubular member for engaging a part carried by a pet cock, and a 10 pet cock provided with a part engaged by said means on the tubular member in communication with the nozzle and fuel chamber, said pet cock providing a part for abutment against said second casing to retain it and the first mentioned casing assembled.

3. In a carbureter, the combination of a casing providing a mixing chamber and a fuel chamber, said mixing chamber provided with a carbureting tube and an auxiliary air 20 inlet, a nozzle in the carbureting tube, a valve for the nozzle, a valve for the auxiliary inlet, and means for operation of the nozzle valve by the auxiliary valve comprising lost-motion connections therebetween, 25 and a pressure-responsive part for movement of said lost-motion connections before movement of the auxiliary valve.

4. In a carbureter, the casing providing a mixing chamber having a carbureting 30 tube and an auxiliary air inlet, carbureting means in the tube, a valve for the auxiliary inlet, connections between said carbureting means and valve, and retard means for said valve, said connections including a movable 35 part having lost-motion connection with said valve, and a pressure-responsive part, operable independently of said retard means, for moving said connections.

5. In a carbureter, a casing providing a 40 mixing chamber having a carbureting tube and an auxiliary air inlet, carbureting means in the carbureting tube, a closure for said auxiliary inlet including a diaphragm, a diaphragm-carried part, and a valve, connections between said diaphragm-carried part and said carbureting means, means for holding said inlet valve closed controlled by the diaphragm, and retard means for said valve.

50 6. In a carbureter, a casing providing a mixing chamber having a carbureting tube and an auxiliary air inlet, carbureting means in the carbureting tube, a valve for said auxiliary inlet including a frame, and a 55 diaphragm secured thereto near its edges, a

stem carried by said frame, and a diaphragm-carried part loose on said stem, a retard means associated with said stem, and operating connections between said diaphragm-carried part and said carbureting means.

7. In a carbureter, a casing providing top and bottom walls and an intermediate wall dividing the mixing chamber from an air chamber, carbureting means for said mixing chamber, said three walls having alining openings therein, a valve for the opening in the top wall, a closure for the opening in the bottom wall, retard means carried by said latter closure, a stem between said valve and retard means, and means on the stem for operation of the carbureting means in accordance with movements of the valve.

8. In a carbureter, a casing providing a mixing chamber having outlet and fuel inlet 75 openings, and an auxiliary air inlet, a pressure-responsive valve therefor, a nozzle in the fuel inlet, and pressure-responsive means to operate said nozzle, said pressure responsive means interconnected with the air valve 80 and adapted and arranged to respond to pressure more quickly than said valve for the auxiliary air inlet.

9. In a carbureter, the combination of a casing providing a mixing chamber having 85 a carbureting tube and an auxiliary air inlet, a nozzle valve in the carbureting tube, air pressure-responsive means for operating said nozzle valve, and retarded air pressure-responsive means interconnected with the 90 nozzle valve to control said auxiliary air inlet.

10. In a carbureter, a casing providing a mixing chamber and a fuel chamber, said casing being shaped to provide a primary 95 air inlet passing around the fuel chamber in contact with the walls thereof to a space below said fuel chamber, and a carbureting tube passing concentrically through the fuel chamber and communicating at its lower 100 end with the space below the fuel chamber and at its upper end with the mixing chamber.

In testimony whereof I hereunto set my hand in the presence of two witnesses.

RAY W. HARROUN.
